UNITED STATES PATENT OFFICE.

CHARLES S. HEFFNER, OF PITTSBURGH, PENNSYLVANIA.

CIGARETTE CARTON.

Application filed June 30, 1922. Serial No. 571,855.

To all whom it may concern:

Be it known that I, CHARLES S. HEFFNER, a citizen of the United States, residing at Pittsburgh, in the county of Allegheny and State of Pennsylvania, have invented certain new and useful Improvements in a Cigarette Carton, of which the following is a specification.

The present invention relates to a carton especially adapted for receiving cigarettes and the like and has for its principal object to provide means for supporting matches so that the same will be conveniently accessible.

Another important object of the invention is to provide a device of this nature which may be manufactured at a comparatively low cost, durable, compact, reliable, and well adapted to the purpose for which it is designed.

With the above and numerous other objects in view as will appear as the description progresses, the invention resides in certain novel features of construction, and the combination and arrangement of parts as will be hereinafter more fully described and claimed.

In the drawing:—

Figure 1 is a perspective of the carton showing the same in an open position.

Figure 2 is a transverse section taken therethrough, and

Figure 3 is a longitudinal section taken therethrough.

Referring to the drawing in detail it will be seen that the carton consists of the box 1 which may be of any preferred construction having hinged thereto the cover 2 which also may be of any preferred construction. In the present modification I have shown the box 1 constructed with the inner box like structure 3 having the strip 4 arranged thereabout adjacent its lower edge so as to form a shoulder for the box like cover 2 which abuts the upper edge of the strip when in a closed position.

My invention consists in housing a plurality of matches conveniently in the cover 2 so as to not interfere with the contents of the box 1 and I accomplish this by providing a hinged leaf 5 which has one longitudinal edge preferably pasted to the inside

of the cover 2 and supports a plurality of matches 6 upon one side thereof preferably the upper side or the side adjacent the cover 55 2 so as to not come into contact with the contents of the box 1. I preferably mount these matches 6 upon the leaf 5 by pasting the sticks or stems thereof to the leaf so that the matches may be readily and easily 60 removed for use when desired.

It will readily be seen that I have provided a compact structure wherein both cigarettes may be carried thus obviating the necessity of a cigarette user in carrying both a cigarette receptacle and a match receptacle or some other lighting device or devices. It will also be seen that the addition of the match carrying feature may be incorporated in the ordinary cigarette carton at a minimum expense and without any enlargement thereof.

The present disclosure of my invention has been given by way of example the same referring only to the preferred construction 75 and it is to be understood that numerous changes may be made in the details of construction and in the combination and arrangement of parts without departing from the spirit of the invention as hereinafter claimed.

Having thus described my invention what I claim as new is:—

In combination, a carton including a box and a cover therefor, said box including a box-like structure and a strip arranged thereabout on its interior adjacent its bottom end, said cover being of a box-like structure and adapted to rest on said strip when in closed position, a leaf hingedly mounted 85 in the cover forming a closure therefor and positioned so as to rest on the edge of the box when the cover is in a closed position, and matches detachably secured to the leaf so as to be entirely encased within the box-like structure of the cover and the leaf when said leaf is closed in relation to the cover.

In testimony whereof I affix my signature in presence of two witnesses.

CHARLES S. HEFFNER.
